UNITED STATES PATENT OFFICE.

EMERY A. STEWART, OF SIOUX CITY, IOWA.

RAILWAY-SWITCH LOCK.

1,333,784.

Specification of Letters Patent. Patented Mar. 16, 1920.

Application filed November 30, 1918. Serial No. 264,842.

To all whom it may concern:

Be it known that I, EMERY A. STEWART, a citizen of the United States, and a resident of Sioux City, in the county of Woodbury and State of Iowa, have invented certain new and useful Improvements in Railway-Switch Locks, of which the following is a specification.

The invention has for its primary object 10 the production of an improved self-locking railway switch.

Another object of the invention is the production of a railway switch embodying a self-acting lock which supplants the commonly 15 used padlock which often is lost or left unlocked by the switchman.

Another object of the invention is the production of a railway switch of the type having an operating lever to throw the 20 switch; the lever being jointed to be swung into inoperative position into engagement with the frame of the switch and embodying self-acting locking mechanism which automatically locks the lever against retrograde 25 movement when the latter is thrown into engagement with the switch frame.

With these and other objects in view, the invention, consisting in the construction, combination, and novel arrangement of 30 parts, will be fully understood from the following description, reference being had to the accompanying drawings, which form a part of this application, and in which like characters of reference indicate corresponding 35 parts throughout the several views, of which,—

Figure 1 is an elevation of a switch embodying my improvement;

Fig. 2 is an enlarged side elevation of the 40 controlling lever-head, parts being cut away;

Fig. 3 is a front elevation of the same;

Fig. 4 is a plan of the same;

Fig. 5 is a vertical section taken on the line 5—5 of Fig. 4; and

Fig. 6 is a rear elevation of the lever controlling segment.

Although I have illustrated and herein-after described the preferred embodiment of the invention, I would not be understood as 50 being limited to the specific structure chosen for illustration for various alterations and modifications may be made in the details of construction and arrangement of parts, without departing from the spirit and scope 55 of the invention as defined in the appended claims.

Referring now, particularly to Fig. 1, the switch illustrated embodies a frame or pedestal, 7, having at its top a plate, 8. In the pedestal is rotatably mounted a controlling shaft, 9, provided with a crank, 10, connected with the switch rod, 11, which it will be understood, is connected to the rails and by its longitudinal movement when actuated by the shaft, 9, throws the rails or switch 60 points laterally. Above the plate, 8, the shaft, 9, carries a fixed lever-head, 12, having a toothed segment, 13, intermeshed with a toothed segment, 14, mounted on the target shaft, 15, rotatably supported on the 70 pedestal. The free end of the head, 12, is bifurcated as at 16, to inclose the end of the lever handle, 17, pivoted therein, to swing in a plane at right angles to the plane in which the lever head swings. When in operative position the handle, 17, is swung in 75 the direction of the frame and into engagement with notches, 18, in the frame member, 8, thus preventing movement of the lever-head. The structure above defined represents no part of the present invention, but 80 serves to illustrate that type of railway switch with which the device of my invention is, perhaps, best applied.

In the construction of my device the lever 85 handle, 17, is fixed on its pivot pin, 19, which is journaled in the bifurcated portion of the lever-head, 12, and carries a fixed segment, 20, freely inclosed within the head. Within the head is a bell-crank 21, fulcrumed as at 22, to the head; one arm of the said bell-crank being provided with a shoulder, 23, engageable with a shoulder, 24, on the segment, the said shoulders being so positioned and related as to prevent 95 rotation of the segment in a direction to permit the lever handle to be swung out of engagement with the notch, 18, of the switch frame. The other side of the segment, 20, is provided with a shoulder, 25, engaging 100 one end of the plunger, 26, the opposite end of which engages the other arm of the bell-crank; the said bell-crank arm being held yieldably in engagement with the plunger as by a compression spring, 27, interposed 105 between the said arm and lever head. As the lever is swung toward its inoperative position the segment coacts with the plunger, 26, and the adjacent bell-crank arm to throw the shouldered bell-crank arm into 110 engagement with the segment. By disengaging the shouldered bell-crank arm from

the segment it is clear the lever handle may then be swung to its operative position. The side of the shouldered bell-crank arm adjacent the segment is provided with a laterally disposed finger, 28, which enters an opening, 29, in the case, 30, of a suitable spring lock embedded within the lever head, which in the present embodiment includes a crescent-shaped lock-bolt, 31, pivoted on a pin, 32, within the case and engageable at one end within an opening, 33, in the finger, 28, the other end portion of the lock-bolt being provided with a slot, 41, through which a stud, 42, on the case, 40 protrudes to limit the movement of the lock-bolt; and a sliding plate, 34, carrying a secondary lock-bolt, 35, engageable with the apertured finger and opposite the companion bolt. The lock-bolts are held 45 yieldably toward each other as by a spring, 36. The ends of the lock-bolts are inclined at an angle to the finger whereby the finger may be forced between the bolts to permit their engagement in the opening, 33. The 50 face of the lever-head is covered by a plate, 37, having a key hole, 38, to receive a key (not shown) which rotates on a pin, 39, to throw the lock bolt out of engagement with the finger, 28.

30 It is now clear that when the lever handle, 17, is swung into engagement with the frame or into its inoperative position it is 45 secure against retrograde movement, yet when the lock bolts by the use of the key 50 are disengaged from the bell-crank finger the spring, 27, coacts with the bell-crank to disengage the shouldered arm from the segment shoulder, 24, and then act on the plunger, 26, to turn the segment shoulder, 40 24, to a position out of registration with the shoulder of the bell-crank, whereupon the key may be removed and the lever-handle 45 swung into operative position.

Having thus described my invention, 45 what I claim as new and desire to secure by Letters Patent of the United States, is,—

1. In a railway-switch, a frame, a rotatable switch-rod-controlling shaft, a lateral lever-head fixed on the shaft, a lever-handle 50 pivoted to the head to swing toward the frame substantially at right-angles to the plane of movement of the head, and engageable with the frame to prevent movement of the head, an engageable member 55 carried by the head, means carried by the head engaged with said member by swinging the handle into engagement with the frame, and a lock carried by the head and including a self-acting lock-bolt, and a lock-bolt-keeper carried by said means and engageable by the lock-bolt to prevent disengagement of said means.

2. In a railway-switch, a frame, a rotatable switch-rod-controlling shaft, a lateral 60 lever head fixed on the shaft, a lever-handle

pivoted to the head to swing toward and from the frame substantially at right-angles to the plane of movement of the head and engageable with the frame to prevent movement of the head, an engageable member 70 carried by the handle, means carried by the head engaged with said member by swinging the handle into engagement with the frame, a lock carried by the head and including a self-acting lock-bolt, and a lock-bolt keeper carried by said means and engageable by said lock-bolt to prevent disengagement of said means from the said member 75 and yieldable means to impel the handle from the frame. 80

3. In a railway-switch, a frame, a rotatable switch-rod-controlling shaft, a lateral lever-head fixed on the shaft, a transverse spindle journaled in the head, a lever-handle fixed on the spindle whereby the handle may 85 be swung toward and from the frame at substantially right-angles to the plane of movement of the head, said handle being engageable with the frame to prevent turning of the head, radial projecting means on the spindle within the head, means within the head movable into and out of engagement with the projecting means, mechanism actuated by movement of the handle toward the frame to move said second means into 90 engagement with the projecting means, and a lock operable to prevent disengagement of said second means from the projecting means.

4. In a railway-switch, a frame, a rotatable switch-rod-controlling shaft, a lateral lever-head fixed on the shaft, a transverse spindle journaled in the head, a lever-handle fixed on the spindle whereby the handle may be swung toward and from the frame 100 at substantially right-angles to the plane of movement of the head, said handle being engageable with the frame to prevent turning of the head, radially projecting means on the spindle within the head, an arm 105 pivoted in the head to swing toward and from the projecting means, and swung into engagement with the projecting means by swinging of the handle toward the frame, to prevent rotation of the spindle, and a lock in the head operable to prevent swinging of said arm from the projecting means. 110

5. In a railway-switch, a frame, a rotatable switch-rod-controlling shaft, a lateral lever-head fixed on the shaft, a transverse 115 spindle journaled in the head, a lever-handle fixed on the spindle whereby the handle may be swung toward and from the frame at substantially right-angles to the plane of movement of the head, said handle being engageable with the frame to prevent movement of the head, radially projecting means on the spindle within the head, an arm 120 pivoted within the head to swing toward and from the projecting means, held yield- 125

ably from the projecting means, and swung into engagement with the projecting means by swinging of the handle toward the frame, to prevent rotation of the spindle, and a lock operable to prevent retraction of the arm.

6. In a railway-switch, a frame, a rotatable switch-rod-controlling shaft, a lateral lever-head fixed on the shaft, a transverse spindle journaled in the head, a lever-handle fixed on the spindle, whereby the handle may be swung toward and from the frame at substantially right-angles to the plane of movement of the head, said handle being engageable with the frame to prevent movement of the head, radially projecting means on the spindle within the head, an arm pivoted within the head to swing toward and from the projecting means, and swung into engagement with the projecting means by swinging of the handle toward the frame, to prevent rotation of the spindle, and a lock automatically engaged with the arm when the latter is swung into engagement with the projecting means, to prevent retraction of the arm.

7. In a railway-switch, a frame, a rotatable switch-rod-controlling shaft, a lateral lever-head fixed on the shaft, a transverse spindle journaled in the head, a lever-handle fixed on the spindle, whereby the handle may be swung toward and from the frame at substantially right-angles to the plane of movement of the head, said handle being engageable with the frame to prevent movement of the head, radially projecting means on the spindle within the head, a bell-crank fulcrumed to the head, one arm thereof being engageable with the projecting means to prevent rotation of the spindle, a connection between the other bell-crank arm and said means, operable as the handle is swung toward the frame, to force said first arm into engagement with the projecting means, and a lock operable to prevent disengagement of said arm from said means.

In testimony whereof, I have hereunto set my hand this 16th day of November, 1918.

EMERY A. STEWART.
